Attorney.*

UNITED STATES PATENT OFFICE.

JOHN S. EDDY, OF LOS ANGELES, CALIFORNIA.

FOUNTAIN SHAVING-BRUSH.

1,374,724.

Specification of Letters Patent. Patented Apr. 12, 1921.

Application filed July 6, 1920. Serial No. 394,245.

To all whom it may concern:

Be it known that I, JOHN S. EDDY, a citizen of the United States, and a resident of Los Angeles, in the county of Los Angeles, 5 State of California, have invented new and useful Improvements in Fountain Shaving-Brushes, of which the following is a specification.

This invention relates to shaving brushes 10 of the character disclosed in my two applications for patent, filed, respectively, January 28, 1920, and June 10, 1920, and numbered respectively, 356,413 and 389,759, and the object of the present invention is to provide 15 an improved form of valve device for regulating the application of the soap to the brush.

In the accompanying drawing, forming a part of this application, I have illustrated 20 one practical embodiment of my invention, subject to modification, within the scope of the appended claims, without departing from the spirit of my invention.

In said drawing:

25 Figure 1 is an external view of my improved brush with the several parts assembled for use.

Fig. 2 is a longitudinal section of the same with the valve closed.

30 Fig. 3 is a transverse section of the same on line 3—3 of Fig. 2.

Fig. 4 is an external fragmentary view of the valve tube.

35 Fig. 5 is a longitudinal section of the same showing the valve open.

Fig. 6 is a transverse section of the same on line 6—6.

As shown in my previous applications hereinabove described, my brush comprises 40 a main body portion B, a liquid holding handle H, a cap C fitting on the handle, a brush holder $\bar{h}$ and a brush b suitably mounted on said holder.

45 Cap C is threaded to screw on the outer end 1 of the handle H and forms a closure for the chamber 2 therein which is adapted to hold a quantity of liquid soap, the outer end of said handle being preferably larger than the inner end thereof so as to form a convenient grip for the hands of the user. The outer end of handle H and cap C have knurled beads 3 and 4, respectively, by means of which these parts may be assembled and disassembled for any purpose.

50 The inner portion of handle H has a turned cylindrical portion 5 fitting a bore

6 in the outer end of body B and a smaller threaded portion 7 fitting a correspondingly threaded portion 8 of the body and a still smaller turned portion 9 fitting the portion 10 of the body, as shown in Fig. 2. The brush end of the handle H has an elongated tubular extension 11 either integrally formed therewith or attached thereto and forming a continuation of the handle, the 65 said extension having a passage 12 therein which opens into the liquid chamber 2 of the handle at its inner end and is open at its other end, as shown.

Body B has a tubular extension 13 thereon which is attached to or formed on the web 14 of said body and projects into the central portion of the brush b for a substantial distance. Said extension has a closed end 15 with a semi-spherical knob 16 75 on its inner side, against which the correspondingly tapered end portion 17 of the extension 11 is adapted to fit, the extension 11 being snugly fitted into the extension 13, as shown in Fig. 2. A plurality of peripheral apertures 18, 18, etc., are formed in the end of the extension 11, and the extension 13 serves to close said apertures when extended as shown in Fig. 2, and to permit the discharge of the liquid therefrom 85 when open as shown in Fig. 5.

Brush holder $\bar{h}$ is threaded on the brush end of the body B and the bristles are held in any suitable manner in the brush body 19 which may be pressed into the holder $\bar{h}$, 90 as shown, or otherwise.

It will be apparent that when the handle H is turned in the body B the tube 13 will be correspondingly moved longitudinally of the tube 11 for opening and closing the 95 valve formed in the extreme of member 11. When said valve is open the brush may be shaken slightly for discharging a suitable quantity of the soap into the center of the brush bristles b and then closed again. The 100 character of the valve as shown and described provides a leak-proof receptacle, easy of operation for obtaining the necessary quantity of soap when desired and free from complicated parts and operations. 105 The arrangement of the handle and body connections insures against leakage, because of the several different sized portions of the handle and the knurled beads provided on the different parts provide a ready 110 means of assembling and disassembling the brush for any purpose, the beads 21 and 22

on the body and on the holder *h*, respectively, being of the same character as those on the handle *H* and cap *C*.

I prefer to make the apertures 18 elongated and narrow, as shown, so that only a slight movement of the handle relative to the body will be necessary for obtaining the required quantity of soap for an operation of the brush, but these and other details 10 may be modified for adapting the brush for use.

What I claim is:

1. A fountain shaving brush having body and handle members and a brush on said 15 body member, said handle member having a liquid holding chamber therein, telescoping extensions on said handle and body members, said handle extension being open and said body extension being closed at one 20 end, the adjacent end of said handle being adapted to seat on said closure for closing the same and outlet means in said outer extension for discharging the liquid.

2. A fountain shaving brush having body 25 and handle members and a brush held on said body member, a soap chamber being provided on the interior of said handle member, a tubular extension centrally of said body member and projecting into the 30 center of said brush, said extension being closed at its outer end and having peripheral orifices therein, a tubular extension on said handle member communicating with said chamber and fitting the interior of said body extension and adapted to be adjusted longitudinally of said body extension for opening and closing said orifices when said handle is adjusted relative to said body.

3. A fountain shaving brush comprising 40 body, handle and brush members, telescoping outer and inner tubular extensions on said body and handle members, respectively, said outer extension being closed at its

outer end and having outlets in the periphery thereof, said inner extension being open 45 at its outer end and arranged so that a movement of said handle will effect a longitudinal movement thereof for opening and closing said outlets, for the purpose described. 50

4. A fountain shaving brush having screw threaded body and handle members and a brush held on said body, and telescoping tubular extensions on said body and handle, respectively closed and open at 55 their outer ends, said outer extension having peripheral outlets near its closed end and an internally extending closure for the end of said handle extension, said handle being adjustable longitudinally of said body 60 and said inner extension being correspondingly adjustable in said outer extension for opening and closing said outlets when said handle is adjusted, as described.

5. A fountain shaving brush including a 65 body member having a brush held thereon and having a tubular extension thereon projecting into said brush and closed at the end, a handle having an extension telescoping into said body portion and open at 70 the end, said body portion being provided with a closure for the end of said handle extension, and peripheral outlets formed adjacent thereto, for providing a valve for regulating the supply of soap to the brush, 75 the movement of said handle in said body serving to adjust said handle extension longitudinally of said body portion for opening and closing said outlets and for seating the end of said handle extension on said 80 closure.

JOHN S. EDDY.
